CLAIM

We claim the ornamental design for an airbed pump control panel, as shown and described.

DESCRIPTION

FIG. 1 is a perspective view of a control panel for use with a pump of an airbed, where the airbed is shown in broken lines;

FIG. 2 is an upper right perspective view of the control panel of FIG. 1;

FIG. 3 is an upper left perspective view of the control panel of FIG. 1;

FIG. 4 is a lower left perspective view of the control panel of FIG. 1;

FIG. 5 is a lower right perspective view of the control panel of FIG. 1;

FIG. 6 is a front elevational view of the control panel of FIG. 1;

FIG. 7 is a right side elevational view of the control panel of FIG. 1;

FIG. 8 is a left side elevational view of the control panel of FIG. 1;

FIG. 9 is a top plan view of the control panel of FIG. 1; and, FIG. 10 is a bottom plan view of the control panel of FIG. 1.

The broken lines in FIGS. 1-6 and 10 represent unclaimed portions of the control panel and form no part of the claimed design.
